(57) **CLAIM**

The ornamental design for a digital audio disc player for an automobile, as shown and described.

DESCRIPTION

FIG. 1 is a perspective view of a digital audio disc player for an automobile showing our new design in an operating condition;

FIG. 2 is a front view of the embodiment shown in FIG. 1; FIG. 3 is a rear view of the embodiment shown in FIGS. 1-2; FIG. 4 is a right side view of the embodiment shown in FIGS. 1-3;

FIG. 5 is a left side view of the embodiment shown in FIGS. 1-4;

FIG. 6 is a top view of the embodiment shown in FIGS. 1-5; FIG. 7 is a bottom view of the embodiment shown in FIGS. 1-6;

FIG. 8 is another front view showing our new design, with the digital audio disc player in a non-operating condition; and,

FIG. 9 is another perspective view showing our new design, with a face lid in an open position.

FIG. 2 is on a enlarged scale.

The broken line showing on FIGS. 1-2 is for illustrative purposes only and forms no part of the claimed design.
